UNITED STATES PATENT OFFICE

HARRY J. BAUGH AND FRED E. KLING, OF YOUNGSTOWN, OHIO

CONVEYING AND DUMPING APPARATUS

Application filed June 25, 1930. Serial No. 463,731.

This invention relates to a method of and apparatus for conveying and handling coils delivered by a coiling machine whereby the coils are transferred and cooled with a minimum use of crane hoist and labor.

It is among the objects of the invention to provide a combination of conveyor and handling elements which shall be adapted to receive coils from the coiling machine or former 10 with the coils in a flat or horizontal position, convey said coils during a timed interval to cool them sufficiently to prevent distorting and sagging, dump said coils from an initial conveying means to a second conveying 15 means and simultaneously turn them down to a vertical position, set the coils on flights of said conveyor and finally convey the coils to a point of loading, the coil handling and conveying operations being conducted at such a rate that the coils are sufficiently cooled for shipment.

These and other objects will become more apparent from a consideration of the accompanying drawings in which like reference 25 characters designate like parts and in which—

Figure 1 is a side elevational view of a conveyor mechanism cooperating at one end with a coil former and at its other end with a dumping mechanism;

Figure 2 is a top plan view of a dumping mechanism;

Figure 3 is a side elevational view of Figure 2, illustrating a portion of a second conveyor mechanism.

Figure 4 is a front elevational view of the mechanism shown in Figure 3.

Figure 5 is a side elevational view showing the dumping mechanism and cooperating conveyor.

Figure 6 is a side elevational view of an enlarged end portion of the conveyor.

With reference to the several figures of the drawings the reference character 1, Figure 1, generally designates a conveyor inclined 45 from a horizontal position, the conveyor terminating at one end adjacent a coiler, a portion of which is designated at 2, and the other end terminating at a receiving platform 3.

The conveyor 1 is of the endless chain or

belt type and is operated through suitable actuating mechanism such as a motor and gear drive operatively connected to the drive wheel 4, Figure 1.

With reference to Figure 5 of the drawings, the receiving platform 3 of the conveyor mechanism 1 is illustrated at one end of a second conveyor mechanism, generally designated at 6, one end of which extends to a shipping platform. The conveyor 6 is of the endless type and is provided with flights 7 which are more clearly illustrated in the enlarged view of Figure 6. The flights may be provided with stakes or spacing bars 8 which support the ends of the coils to prevent their sagging. The conveyor 6 is provided at one end with a tension device generally designated at 9, which comprises an adjustable screw member for adjusting a journal bearing 10 in a horizontal position, the bearing 10 supporting a conveyor drum which is thereby spaced to adjust the tension on the conveyor 6.

The journal bearing 10 is supported in a frame structure 11 on which is mounted a dump mechanism generally designated at 12. Inclined bars 13 are carried by frame 11 and levers 14 having hooked ends or stops 15 are pivotally mounted on the bars 13 at 16. The levers 15 are operative through suitable linkage 17 and a lever 18 to release the coils whereby they are permitted to slide down on the inclined bars 13 into engagement with a dumper casting 19.

The dump mechanism is more clearly illustrated in connection with Figures 2, 3 and 4 of the drawings, and consists of the dumper 19 which is carried by an arm 20 that is pivotally mounted at 21 to the supporting frame structure 11. The full lines of Figure 3 show the dumper in its dumping position and the light lines show it in its upper or coil receiving position with the stop lever 14 in the stop position. The casting 19 is provided with an abutment 22 which engages the coils and prevents them from sliding off during the tilting movement of the casting.

The arm 20 is connected to a link 23 pivoted at one end to a crank 24 of a gear drive mechanism operated by a motor 25. The

dump casting 19 is in the path of movement of the flights 7 of the conveyor 6, as is clearly shown in Figure 4, and when the dump casting is tilted to the position shown in Figure 3, the coils are turned down into the flights 7 of the conveyor.

The operation of the coil handling and conveying mechanism is briefly as follows: The coils are received from the coiler at 2 and carried by conveyor 1 to the delivery table 3. The coils are disposed in a flat horizontal position on the conveyor 1 and in this position the bands which hold the coils together are applied.

When the coils are raised at the end of the conveyor 1 at 3, they slide on the inclined bars 13 and come to rest against the stop 15 of lever 14. When the dump casting 19, thru its actuating mechanism, is raised to parallelism with the inclined bars 13 the operator through lever 18 trips the stop 15 and permits the coil to slide to the abutment 22 of the dump casting, and the dumping mechanism by tilting the casting 19, turns down the coil into the flights 7 of the conveyor and in vertical position.

The flights of the conveyor 6 are then moved a distance equal to the width of the coil and the coil dumper is returned to its upper position. By regulating the extent of movement of conveyor 6, the coils can be packed closely or spaced as far apart as desired, and they may also be placed on the conveyor in batches with sufficient clearance between the batches to thread a rope or chain through the coils for lifting them with a crane to load them into cars.

By utilizing the stakes or uprights 8, coils made of narrow strips are prevented from falling over.

Although the method of handling and conveying coils contemplates placing them in horizontal positions on conveyor 1, and in vertical position on conveyor 2, the handling mechanism may be utilized to handle the coils in their flat or horizontal position on both conveyors by pulling the coils from the dumper with a hook and stacking them on the flights and on each other if desired. To stack the coils, it is only necessary to rest the second conveyor mechanism after the first coil has been taken off and to deliver the next coil on top of the previous one.

It is evident from the foregoing description of this invention that coil handling and conveying mechanism formed in accordance therewith provides simple and effective means for handling coils with a minimum amount of labor, and the cycle of the operations may be controlled to allow sufficient cooling of coils to permit loading them directly into cars for shipment, without causing injury to the cars.

Although one embodiment of the invention has been herein illustrated and described, it

will be obvious to those skilled in the art that various modifications may be made in the details of construction without departing from the principles herein set forth.

We claim:

1. A coil handling apparatus comprising a combination with a pair of conveyers arranged at different levels and one in advance of the other, of a coil transferring device between said conveyers, said device comprising a supporting frame structure, a plurality of inclined skid bars mounted on said frame and having their upper ends terminating adjacent the discharge end of the upper of said conveyers and their lower ends terminating a material distance above the receiving end of the lower of said conveyers, a coil dumping device pivotally mounted on said frame and adapted to be swung from a position between and below said skid bars down into a substantially vertical position below the top surface of the lower conveyer, a link for actuating said dumping device, power means for operating said link, stops pivotally mounted on at least some of said skid bars and adapted to engage and hold coils delivered to said bars until said coil dumping device is in position to receive said coils, means for moving said stops into inoperative position to release the coils, and means on said dumping device for stopping the coils as they move into position thereon and for retaining the coils on said device during its downward movement.

2. A coil handling apparatus comprising a combination with a pair of conveyers arranged at different levels and one in advance of the other, of a coil transferring device between said conveyers, said device comprising a supporting frame structure, a plurality of inclined skid bars mounted on said frame and having their upper ends terminating adjacent the discharge end of the upper of said conveyers and their lower ends terminating a material distance above the receiving end of the lower of said conveyers, a coil dumping device pivotally mounted on said frame and adapted to be swung from a position between and below said skid bars down into a substantially vertical position below the top surface of the lower conveyer, power means for actuating said dumping device, means for holding the coils delivered onto said skid bars by the upper of said conveyers until said coil dumping device is in position to receive them and means on said dumping device for stopping the coils as they move into position thereon and for retaining the coils on said device during its downward movement.

3. A coil handling apparatus comprising in combination a supporting frame, a plurality of inclined skid bars rigidly mounted on said frame, a coil dumping device pivotally mounted on said frame and adapted

to be swung from a position between and below said skid bars down into a substantially vertical position, a link for actuating said dumping device, power means for 5 operating said link stops pivotally mounted on at least some of said skid bars and adapted to engage and hold coils delivered to said skid bars until said coil dumping device is in position to receive them, means for moving said stops into inoperative position to 10 release the coils and means on said dumping device for stopping the coils as they move into position thereon and for retaining the coils on said device during its downward 15 movement.

In testimony whereof, we have hereunto set our hands.

HARRY J. BAUGH.
